US00D891535S

(12) **United States Design Patent** (10) Patent No.: **US D891,535 S**
(45) Date of Patent: **** Jul. 28, 2020**

(54) **ROBOT**

(71) Applicant: **Koelnmesse GmbH**, Cologne (DE)

(72) Inventor: **Andreas Bauer**, Nuremberg (DE)

(**) Term: **15 Years**

(21) Appl. No.: **35/506,963**

(22) Filed: **Feb. 20, 2019**

(80) **Hague Agreement Data**

Int. Filing Date: **Feb. 20, 2019**

Int. Reg. No.: **DM/201388**

Int. Reg. Date: **Feb. 20, 2019**

Int. Reg. Pub. Date: **Jun. 21, 2019**

(51) LOC (12) Cl. **21-01**

(52) U.S. Cl.

USPC **D21/578**

(58) **Field of Classification Search**

USPC D21/582; D15/199

CPC A63H 3/04; A63H 11/00; A63H 33/003

See application file for complete search history.
